[57] CLAIM

The ornamental design for a toilet/bidet cabinet, substantially as shown and described.

DESCRIPTION

FIG. 1 is a front elevational view of a toilet/bidet cabinet showing our new design;

FIG. 2 is a right side elevational view, the left elevational view being a mirror image thereto;

FIG. 3 is a rear elevational view thereof;

FIG. 4 is a top plan view; and

FIG. 5 is a bottom plan view thereof.
